US00D983049S

(12) **United States Design Patent** (10) Patent No.: **US D983,049 S**
McCree et al. (45) Date of Patent: **** Apr. 11, 2023**

(54) CARRIER FOR CONTAINERS	2,397,376 A	3/1946	Caldwell
(71) Applicant: Graphic Packaging International, LLC , Atlanta, GA (US)	2,397,716 A	4/1946	Wendler
(72) Inventors: Justin McCree , Bristol (GB); Steve M. Gould , Bristol (GB)	2,522,950 A	9/1950	Keith
(73) Assignee: Graphic Packaging International, LLC , Atlanta, GA (US)	2,594,376 A	4/1952	Arneson
(**) Term: 15 Years	2,594,377 A	4/1952	Arneson
(21) Appl. No.: 29/775,557	2,737,326 A	3/1956	Toensmeier
(22) Filed: Mar. 24, 2021	2,798,603 A	7/1957	Grinspoon
(51) LOC (14) Cl. 09-03	2,950,041 A	8/1960	Stone
(52) U.S. Cl. D9/752	2,965,410 A	12/1960	Hughes
(58) Field of Classification Search	3,001,647 A	9/1961	Liss
USPC D9/751-755, 414, 415, 424, 425, D9/432-433, 503, 504, 715, 737, 756, D9/759, 760, 761; D3/273, 201, 283, D3/284, 286, 295, 903; 220/669-673, 220/675, 574-575, 573.1; D11/143; 206/148, 427, 161; 294/87.2; D7/601-602, 550.1, 553.1, 554.1, 554.3, D7/555, 557	3,046,711 A	7/1962	Harrison

CLAIM

The ornamental design for a carrier for containers, as shown and described.

DESCRIPTION

FIG. 1 is a first embodiment perspective view of a carrier for containers showing our new design, shown in a position of use with exemplary containers.

FIG. 2 is a left elevation view of the carrier for containers of FIG. 1, the right elevation view is a mirror image.

FIG. 3 is a front elevation view of the carrier for containers of FIG. 1, the rear elevation view is a mirror image.

FIG. 4 is a top plan view of the carrier for containers of FIG. 1.

FIG. 5 is a bottom plan view of the carrier for containers of FIG. 1

FIG. 6 is a plan view thereof, shown independent of the exemplary containers to show aspects of the design not visible when combined, and further in an unfolded configuration.

FIG. 7 is a second embodiment perspective view of a carrier for containers showing our new design, shown in a position of use with exemplary containers.

FIG. 8 is a left elevation view of the carrier for containers of FIG. 7, the right elevation view is a mirror image.

FIG. 9 is a front elevation view of the carrier for containers of FIG. 7, the rear elevation view is a mirror image.

FIG. 10 is a top plan view of the carrier for containers of FIG. 7.

FIG. 11 is a bottom plan view of the carrier for containers of FIG. 7; and,

FIG. 12 is a plan view thereof, shown independent of the exemplary containers to show aspects of the design not visible when combined, and further in an unfolded configuration.

The broken lines are shown for the purpose of illustrating parts of the article as well as environmental subject matter of exemplary containers. None of the broken lines form part of the claim.
